UNITED STATES PATENT OFFICE

EDWARD E. MASTON, OF CHICAGO, ILLINOIS, ASSIGNOR TO MID-WEST BOX COMPANY,
OF CHICAGO, ILLINOIS, A CORPORATION OF DELAWARE

MACHINE FOR MAKING CORRUGATED BOARD

Application filed October 22, 1926. Serial No. 143,331.

The invention relates to machines for making corrugated board.

One object of the invention is to increase the output of the machine by providing means to expedite the setting of the adhesive used to secure the corrugated and facing sheets together so the single-faced product may be immediately fed to a double-facer or otherwise disposed of.

10 Another object of the invention is to provide a machine which is adapted to operate at high speed to produce a waterproofed product in which a hot adhesive, such as asphalt, is used to secure the sheets together.

15 Another object of the invention is to provide a corrugating machine with means to expedite the setting of different kinds of adhesives used in making different products, such, for example, as silicate of soda and asphalt. This object is attained primarily by providing means to heat the paper when an adhesive which is expedited by heat, such as silicate of soda, is used, and to cool a hot adhesive, such as asphalt, to unite the corrugated and facing sheet.

Other objects of the invention will appear from the specification.

The invention consists in the several novel features hereinafter set forth and more particularly defined by claims at the conclusion hereof.

In the drawings: Fig. 1 is a side elevation of a machine embodying the invention, parts being broken away for purposes of illustration. Fig. 2 is a central longitudinal section. Fig. 3 is a side elevation, one frame-side being removed and parts shown in section. Fig. 4 is a section taken on lines 4-4 of Fig. 3.

40 The invention is exemplified in a machine comprising a suitable frame A comprising complementary sides in which the several mechanisms are mounted; a roll of suitable paper stock B on a shaft carried in bearings *a* of the frame, to form the corrugated sheet B'; a roll of paper stock C on a shaft carried in bearings *a'* of the frame to form the liner or facing sheet C' for the corrugated sheet B'; a pair of intermeshing rollers *b*, *b'* having corrugated intermeshing peripheries 45 to corrugate the sheet B', a roller *b*² for guid-

ing sheet B' from roll B to the corrugating rolls; a drum D having its outer periphery corrugated as at *d* to conform to the corrugated sheet and receiving it from the corrugating roll *b'*; a device for applying adhesive to one face of the sheet C' comprising a pan *c* and an applying roller *c'* to which the sheet is guided by rollers *c*², *c*³ and *c*⁴; rollers *c*⁵ and *c*⁶ which guide sheet C', after the adhesive has been applied thereto, to the corrugated sheet on the periphery *d* on the drum D; a series of hollow shoes E circumferentially arranged around the drum; and rollers *c*¹⁴ and *c*¹⁵ for guiding the finished board from the machine.

Corrugating rolls *b* and *b'* are hollow and heated by steam or any other suitable heating agent received through pipes *b*²⁰ and discharged through pipes *b*²¹, as well understood in the art. Fingers *b*¹⁰ guide the corrugated sheet around and hold it in the corrugations at one side of the roll *b'*. Fingers *b*¹¹ strip the corrugated sheet from roll *b'* and guide it to the corrugated periphery of drum D. Drum D is spaced from and does not mesh with the corrugating roll *b'* to prevent heat transference between them. This spacing is an important feature because in cooling the drum it is desirous to prevent the cooling medium from cooling the corrugating roll *b'* and to prevent the latter heating the drum D.

Each of the shoes E is hollow for the circulation of a suitable temperature changing medium and has a smooth arcuate inner periphery *e*. An inlet pipe *e*' and an outlet pipe *e*² are connected to deliver a fluid into the shoe and to discharge it. The periphery *e* of each shoe conforms substantially to the facing sheet passing around with and to the drum D so that it will be adapted to contact with the outer face of said sheet to iron the sheet as it slides along the shoe and to press the sheets together.

Each shoe is pivotally supported so it may position itself against, and adapt itself to any irregularities in, the facing sheet on the drum; is spring pressed to exert the desired force necessary to insure bonding contact between the crowns of the corrugated sheet and the facing sheet to which adhesive has been 100

applied and firm contact for heat transference from the shoes to the facing sheet and adhesive to accelerate the drying or setting of the adhesive; and is adjustable to operate with varying thicknesses of sheets. Each shoe is provided at either end with a stud e^4 which is guided and has a limited movement in a radial slot e^5 . Slots e^5 are confined in brackets e^6 which are adjustable and slide radially in ways a^4 formed in the sides of frame A. Screws e^7 are provided to adjust the brackets e^6 to and from the drum. Springs e^8 are interposed between each shoe and a cross-bar of one of the brackets e^6 to yieldingly force the shoe toward the drum D. Screws e^9 are adapted to individually vary the tension of the springs e^8 . These devices permit the shoes to adapt themselves to irregularities in the paper, provide for adjustment of the shoes to compensate for various thicknesses of liners and insure firm and uniform pressure between the inner face of the facing sheet and the crowns of the corrugated sheet to cause the sheets to adhere together and to insure heat-transference between the shoes and the sheets to dry or set the adhesive between them.

The driving mechanism comprises a shaft 10 journalled in frame A; a gear 11 driven thereby and meshing with a gear 12 fixed to the shaft of the corrugating roll b' , the periphery of which meshes with the corrugated periphery of and drive roll b ; a gear 13 meshing with and driven by gear 11; and a gear 14 fixed to the shaft of drum D and meshing with gear 13. Guide roll c^5 for the faced corrugated sheet is driven by means of a sprocket wheel 15 on the shaft of roll b , a chain 16 and a sprocket 17 on the shaft of roll c^5 . If desired, suitable gearing may be provided to drive the rolls B and C, as well understood in the art.

A pipe d^2 is suitably connected to deliver a heating or cooling medium into the drum D so that when an adhesive which will be dried by heat, such as silicate of soda is used, steam or other heating medium may be delivered into the drum to heat it. A discharge pipe d^3 is connected to carry the fluid from the drum.

The inlet pipes e' for delivering fluid into the shoes E and inlet pipe d^2 for the drum D are connected to receive a heating medium such as steam from a supply pipe 20 under control of a valve 21 and are also connected to receive through suitable branch connections 24 a cooling medium, such as brine, or cold water, or air, from a supply pipe 22 under control of a valve 23. In the manufacture of corrugated board, adhesives, such as silicate of soda, are used for ordinary paper stock, while when water-proof board is being formed, a different adhesive, such as asphalt, is used. In order to adapt the machine to expedite the setting of these different adhesives so that the machine may be operated at a

maximum speed, it is necessary to heat the silicate of soda or similar adhesive, and when asphalt is used, it is usually hot and its drying or setting is expedited by the application of a cooling medium. By making provision for either cooling or heating the shoes E, the machine is adapted to expedite the drying and increase the output of the machine either when adhesives are used which are accelerated by cooling or drying. Furthermore, when asphalt is used to secure the sheets together it sometimes occurs that the asphalt cools before the facing sheet is applied thereto and to adapt the machine to this situation, provision is made so that one of the shoes E may be heated, while the others are being cooled so that during the initial portion of the passage of the sheets around the drum D, the asphalt will be heated and thereafter the sheets will be cooled by the remaining shoes with which the facing sheet contacts.

For this purpose the inlet e' for the first of the series of shoes with which the facing sheets contact is connected by a pipe 25 to a branch 26 which is connected to receive steam from supply pipe 20 under control of a valve 27 and to receive a cooling medium from pipe 22 through a branch pipe 28 under control of a valve 29. By means of valves 27 and 29, the shoe may be supplied with a heating medium to soften the asphalt, when desired, before it passes to the remaining shoes which are then being supplied with a cooling medium. Each of the branch pipes 24 and the branch pipe 25 is connected to an inlet e' of one of the shoes by means of a flexible section 30 which leaves the shoes free to move slightly responsively to irregularities in the paper or their adjustment. The outlet pipes e^2 for the shoes are connected by branches 31 to a common outlet pipe 32. Flexible sections 33 between the outlet e^2 and the branch pipes 31 are provided to permit the desired movement of the shoes.

In operation, the sheet B' from roll B will be heated and corrugated in its passage between rolls b and b' . From the latter it will be stripped by fingers b^{11} and guided thereby to the periphery of the corrugated drum D where the face of sheet C' to which an adhesive has been applied by roll c' , will pass into contact with the crowns of the corrugated sheet to secure the sheets together. In its passage around and with the drum D, the facing sheet will be pressed against the corrugated sheet and ironed by the shoes E to insure a close contact. The drying or setting of adhesive will be expedited by the heating or cooling medium flowing through the drum D and the shoes E according to the requirements of the adhesive being used so that the adhesive will be substantially set or dried when it leaves the drum D, from which it may be suitably disposed of or delivered to a double facer machine, such, for

example as the one disclosed in an application for Letters Patent filed by me October 23, 1926, and serially numbered 143,692.

The invention exemplifies a machine for making corrugated board in which substantially stationary shoes are pressed against the facing sheet while it and the corrugated sheet are passing around with the drum to insure close contact and to apply heat or cold to expedite the setting of the adhesive; in which provision is made for heating or cooling the mechanism for applying the facing sheet to adapt the machine for expediting the setting of different adhesives; and a machine of maximum capacity by reason of expediting the setting of the adhesive so that it may be immediately passed, if desired, to a machine for applying a second face to the corrugated sheet. Any suitable heating and cooling media may be used.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a supporting structure, a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, and shoes arranged in a substantially annular series around the drum and adapted to engage the facing sheet, said shoes being radially movable relatively to the drum and operating to press the facing sheet against the corrugated sheet and thereby assist in the setting of the adhesive.

2. In a machine of the character described, the combination of a supporting structure, a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, shoes arranged in a substantially annular series around the drum and movable radially relatively to said drum, and springs applied to shift the shoes inwardly against the facing sheet so as to force the latter against the corrugated sheet and thereby aid in the setting of the adhesive and the uniting of the two sheets.

3. In a machine of the character described, the combination of a supporting structure,

a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, shoes arranged in a substantially annular series around the drum and mounted so as to move radially and to tilt on axes parallel with respect to the axis of the drum, and springs applied to shift the shoes inwardly against the facing sheet so as to force the latter against the corrugated sheet and thereby aid in the setting of the adhesive and the uniting of the two sheets.

4. In a machine of the character described, the combination of a supporting structure, a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, hollow shoes arranged in a substantially annular series around the drum and arranged to engage the facing sheet and press it against the corrugated sheet, and means for delivering fluid to the shoes to accelerate the setting of the adhesive.

5. In a machine of the character described, the combination of a supporting structure, a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, hollow shoes arranged in a substantially annular series around the drum and arranged to engage the facing sheet and press it against the corrugated sheet, and means for accelerating the setting of the adhesive, comprising a pipe system connected to circulate through the shoes either a hot or cold fluid depending upon the nature of the adhesive.

6. In a machine of the character described, the combination of a supporting structure, a pair of coacting rolls for corrugating a sheet of paper, a drum having a corrugated periphery around which the sheet passes after it has been corrugated by the rolls, means for applying a facing sheet to the corrugated sheet on the drum, means for coating one of the sheets with an adhesive prior to the uniting of the two sheets around the drum, hollow shoes arranged in an annular series around the drum and mounted so as to

move radially relatively to said drum and press the facing sheet against the corrugated sheet, and means including flexible piping for circulating a fluid through the shoes to accelerate the setting of the adhesive.

5 Signed at Chicago, Illinois, this 4th day of September, 1926.

EDWARD E. MASTON.
